(57) **CLAIM**

The ornamental design for an instrument for diagnosing and treating soft tissue abnormalities, as shown and described.

DESCRIPTION

FIG. 1 is a view in perspective of an instrument for diagnosing and treating soft tissue abnormalities showing our new design.

FIG. 2 is a view in front elevation of the instrument shown in FIG. 1.

FIG. 3 is a view in rear elevation of the instrument shown in FIG. 1.

FIG. 4 is a top plan view of the instrument shown in FIG. 1.

FIG. 5 is a bottom plan view of the instrument shown in FIG. 1.

FIG. 6 is a view in left side elevation of the instrument shown in FIG. 1; and,

FIG. 7 is a view in right side elevation of the instrument shown in FIG. 1.
